Primary Examiner — Richard E Chilcot

(57) **CLAIM**

The ornamental design for a case, as shown and described.

DESCRIPTION

1. Case

1.1 : Front

1.2 : Back

1.3 : Perspective

1.4 : Left

1.5 : top side

1.6 : open

1.7 : open closed pouch

1.8 : open unfolded pouch

1.9 : open outer pouch

1 Claim, 9 Drawing Sheets(56)
